REFRIGERATING APPARATUS

John W. Craig and Don E. Dasher, Dayton, Ohio,
assignors to General Motors Corporation, Dayton, Ohio, a corporation of Delaware

Application February 28, 1938, Serial No. 192,990

13 Claims. (CL 62—5)

This invention relates to refrigerating apparatus and more particularly to control means for twin generator-absorber refrigerating apparatus.

In twin generator-absorber refrigerating apparatus the generator-absorbers are alternately heated to drive refrigerant alternately from one generator-absorber to the condenser and evaporator when refrigerant is evaporated and the evaporated refrigerant is absorbed in the other generator-absorber which is cooled.

It is an object of our invention to provide an improved means for alternately heating twin generator-absorbers and particularly a means in which no pilot light is required.

It is another object of our invention to provide a control means for a plurality of burners for causing the burners to be alternately supplied with fuel, and for lighting one burner from another during the alternation.

It is still another object of our invention to provide means for decreasing the restriction to the supply of gas and providing the greater flow of gas to the burners during the alternations of the burners.

Further objects and advantages of the present invention will be apparent from the following description, reference being had to the accompanying drawings, wherein a preferred form of the present invention is clearly shown.

In the drawings:

Fig. 1 shows in diagrammatic form a twin generator-absorber type of refrigerating system embodying our invention;

Fig. 2 is an enlarged view of one of the burners and a portion of flash tube employed for lighting one burner from another;

Fig. 3 is a sectional view of the control means for controlling the flow of fuel to the burners shown in Fig. 1; the control means is shown in the position it assumes at the start of a cycle;

Fig. 4 is another view of the control means generally similar to Fig. 3 showing the control means in the position it assumes just before the end of a cycle;

Fig. 5 is a view generally similar to Figs. 3 and 4 in which the alternation of the supply of fuel to the burners is almost completed;

Fig. 6 is a view generally similar to Figs. 3, 4 and 5 showing the control means in the position it assumes at the completion of the alternation;

Fig. 7 is a sectional view taken along the lines 1—7 of Fig. 4;

Fig. 8 is a sectional view of the toggle lever; and

Fig. 9 is a sectional view taken along the lines 9—9 of Fig. 4.

Briefly we have shown a twin-generator-absorber refrigerating system having a condenser connected to each generator-absorber with evaporating means connected in between the two condensers. The generator-absorbers are alternately heated by individual burners controlled by a two-way gas valve operated by fluid pressure systems responsive to the temperatures of the twin generator-absorbers. A throttling valve responsive to evaporator temperature controls the supply of gas to the two-way valve. The two-way valve is provided with dash-pot means incorporated in its fluid pressure operating means which delays the shutting off of fuel to the lighted burner until the other burner can be lighted. A by-pass is provided around the throttling means which is opened during the alternation of the two-way valve from one position to another to provide an added fuel supply.

Referring now to the drawings and more particularly to Fig. 1, there is shown a twin generator-absorber refrigerating system including the twin generator-absorbers 20 and 22 heated by burners 24 and 26 under the control of our improved form of two-way gas valve 28. A refrigerant conduit connects the twin generator-absorbers 20 and 22 and is provided with a condenser portion 30 connected to the generator-absorber 20 and a condenser portion 32 connected to the generator-absorber 22. Connected in between the two condenser portions 30 and 32 are two evaporating portions 34 and 36 which are separated by some suitable form of flow control device 38, such as a restrictor, for providing the pressure drop between the operative condenser portion and the operative evaporating portion. As shown in Fig. 1, the generator-absorber 22 is being heated by the flames issuing from the burner 26 to drive ammonia or other refrigerant from the generator-absorber 22 to the condenser 32 where the refrigerant condenses, passes through the evaporating portion 36 without any evaporation taking place, and thence passes through the restrictor 38 into the evaporating portion 34 where the liquid refrigerant evaporates under reduced pressure and is absorbed by the absorber 20.

The flow of gas to the two-way valve 28 is controlled by a thermostat bulb 40 in heat exchange relation with end portions of the two evaporating portions 34 and 36. This thermostat bulb is connected by a small fluid conduit 55 to a throttling valve 42 connected in the gas

supply conduit 44 for controlling the supply of gas to the two-way valve 28 so as to control the heating of the generator-absorbers in accordance with the temperature of the evaporating portions. The two-way valve 28 is controlled by the thermostat bulb 46 mounted in heat exchange relation with the generator 20 and the thermostat bulb 48 mounted in heat exchange relation with the generator-absorber 22. These two thermostat bulbs 46 and 48 are connected by fluid conduit means with the control valve 28 which is constructed in such a manner that when the operative generator becomes sufficiently warm to indicate that substantially all the refrigerant has been driven from it, the two-way valve is operated to change the supply of gas from the operative burner to the inoperative burner.

The control valve 28 is provided with mechanism for providing a short interval of time in which both burners are supplied with gas, which is sufficiently long to enable the lighting of the burner newly supplied with gas from the burner which has been operative through the medium of a flash tube 50 which conveys burning gases from the lighted burner to the burner which is to be lighted. A by-pass 52 is provided around the throttling valve 42, which is opened during the period in which both burners are supplied with gas so as to insure an adequate supply of gas for lighting the one burner from the other.

Each of the burners are provided with a laterally extending tube 54 which extends into the flash tube 50 for feeding the flash tube with gas so that it is capable of conducting the flame from one burner to another. Each end of flash tube is provided with an upwardly extending portion 56 which feeds the burned and unburned gases into the flame issuing from the burner. Through these means the burners may be lighted from each other and no pilot light is required.

Referring now to the remaining figures of the drawings for a more complete disclosure of the two-way valve 28 there is shown a stamped metal casing 60 provided with a wide reinforcing flange. Upon opposite side walls of the casing 60 there is provided cylinder members 62 and 64 which have an inturned rim each receiving an inner collar, 66 and 67, which receives a clamping member, 68 and 69, threaded into it from the outside of the casing 60. These clamping members are each provided with a tube, 70 and 71, connecting to one of the thermostat bulbs 46 or 48 lodged within the generator-absorbers 20 and 22. The clamping members thus fasten the cylindrical members 62 and 64 to the side walls of the casing.

The inner ends of the sleeves 62 and 64 are provided with a necked portion which extends through apertures in the opposite sides of the bracket 72 and are spun over to fasten the bracket 72 to the sleeves which in turn are fastened to the side walls of the casing 60. The sleeve 62 is provided with a bellows 74 and the sleeve 64 is provided with a bellows 76 sealed to the necked end portion of their respective sleeves 62 and 64. The inner ends of the bellows 74 and 76 carry the ends of bellows follower pins 78 and 80 which have their other ends each provided with a conical point for engaging the levers 82 and 84 which are pivoted upon the pivot buttons 86 and 88 provided upon an upwardly extending portion 90 of a bracket 92 which is fastened by spot-welding or other suitable means to the lower end of the bracket 72.

The upper ends of the levers 82 and 84 are received within the forked ends of the adjusting rods 94 and 96 which are provided with pins extending through short slots in the upper ends of the levers 82 and 84. The rods 94 and 96 are surrounded by the flanged threaded sleeves 98 and 102, which are slidably mounted within directly opposite apertures in the upper portion of the bracket 72. Each of these sleeves 98 and 102 is provided with a compression type coil spring, 104 and 106, which extends between the bracket 72 and the nuts, 108 and 110, which are threaded onto the sleeves 98 and 102. The forked rods 94 and 96 are provided with nuts 112 and 114 at their opposite ends.

The levers 82 and 84 are provided with tongues 116 and 118 which are adapted to engage the upper ends of a common toggle lever 120 which is pivoted upon the button 122 and is provided with a hooked lower end portion extending around the slotted portion of a valve rod 124 which is guided by bushings 126 and 128 provided in the bracket 92. The valve rod 124 is provided with a slot 130 which receives a pin 132 extending through the hooked portion provided at the lower end of the toggle lever 120. The hooked portion also supports the lower end of a tension type toggle spring 134 which extends upwardly and is hooked through an adjusting screw 136 provided in the connecting portion of the bracket 72.

The valve rod 124 is provided with an adjustable cam 138 held in place upon the valve rod by a set screw 140. This cam is adapted to cooperate with the cam follower 142 pivotally connected to the valve seat plug 144 which is clamped to the casing by a threaded fitting 146. This threaded fitting 146 contains a "Duprene" faced valve member 148 which is urged against its seat by a light compression type coil spring 150. The valve 148 is connected to the cam follower 142 by a forked rod 152 which is threaded at one end into the valve member 148 and connected by a pin to the cam follower 142.

The valve rod 124 has cup-shaped members 154 and 156 threaded to its opposite ends which contain valve members 158 and 160 held in place by the concentric springs 162 and 164 which engage a groove provided in each of the cup members inside its rim. The valve members 158 and 160 each have a "Duprene" face which is adapted to engage the mouth of the fittings 166 and 168 provided as outlet valve seats in the side walls of the casing 60. A similar fitting 170 is provided as an inlet valve fitting and connects to the gas supply conduit 44 while the outlet valve fittings 166 and 168 are connected to their respective burners 24 and 26. The by-pass conduit 52 connects to the fitting 146.

60

Operation

The operation of the control valve continues progressively from Fig. 3 to Fig. 6. In Fig. 3 the control valve is shown at the beginning of the cycle illustrated in Fig. 1 in which the burner 26 is heating the generator-absorber 22. The gas flows from the conduit 44 past the throttling valve 42 to the inlet fitting 170 which feeds the gas into the casing 60. The valve rod 124 is moved to a position against the outlet fitting 166 to prevent the flow of gas to the burner 24 while the valve seat member 160 is well away from the fitting 166 so that the gas may flow from the casing 60 to the burner 26. At this time the generator-absorber 22 and thermostat bulb 48

are relatively cool so that the spring 106 is sufficiently strong to overcome the force of low pressure gas within the sleeve 64 and thus hold the lever 84 in fully retarded position. Inasmuch as the burner 24 has just ceased heating the generator-absorber 20 the temperature of the bulb 46 will still be high and the pressure within the sleeve 62 will compress the bellows 14 sufficiently to hold the lever 82 in an outer position against the tension of the spring 104 so that the rim upon the sleeve 98 is held away from the bracket 72 which serves as its stop and the forked end of the rod 94 is away from the adjacent end of the sleeve 98.

As the cycle continues the thermostat bulb 46 will become cooler and the generator-absorber 22 and its thermostat bulb 48 will become warmer as shown in Fig. 4, just before the end of the cycle shown in Fig. 1. A lip 118 of the lever 84 has moved the pivot end of the toggle lever 120 almost to its dead center position. The valve rod 124, however, is still in its extreme left position and is held in that position by the engagement of the cam member 138 with its follower 142. In the meantime, however, the pin 132 at the lower end of the toggle lever 120 has moved to the opposite end of the slot 130. The rim of the sleeve 102 has been pulled away from the bracket 72 and the forked end of the rod 96 has been pulled away from the sleeve 102 by the pressure within the sleeve 64 which has been sufficient to overcome the tension of the coil spring 106.

When the temperature of the thermostat bulb 48 and the generator-absorber 22 becomes sufficiently high it overcomes the retarding force of the cam 138, the toggle spring 134 and the spring 106 to throw the toggle lever 120 across its dead center position into the position as shown in Fig. 5. This causes the valve rod 124 to be moved from its extreme left position as shown in Figs. 3 and 4 across its center position toward the fitting 168 to the position shown in Fig. 5, in which position it permits a comparatively large supply of gas to flow to the burner 24, since the fitting 166 is substantially fully open while a smaller supply of gas is permitted to flow through the fitting 168 to the burner 26. The larger gas flow through the burner 24 tends to draw a flame through the flash tube 50 and light the gas issuing from the burner 24.

It should be noted that the cam follower 142 is provided with a central notch which tends to hold the valve rod for a period in this position which is sufficient to insure lighting of the burner 24 from the burner 26 through the medium of the flash tube 50. The cam 138 by its engagement with the cam follower 142 also opens the by-pass valve 148 which permits gas to flow through the by-pass 52 around the throttling valve 42 directly into the casing 60 so as to insure an adequate supply of gas during the period of alternation regardless of the condition of the thermostat 40 and the throttling valve 42.

The conduits 70 and 71 connecting the sleeves 62 and 64 with the thermostat bulbs 46 and 48 in the generator-absorbers have a restricted cross-section. Since the generator-absorbers are warmer than the two-way control valve 28 the liquid in the fluid thermostat system tends to collect in the sleeves 62 and 64 and a particularly large amount of liquid collects in the sleeve which is connected to the thermostat bulb of the absorber which is absorbing. Thus when the toggle lever 120 is pushed across dead center, the

liquid in the sleeve (in this instance sleeve 62) delays the complete movement of the toggle lever 120 and the valve rod 124 until sufficient fluid can escape from the sleeve 62 under the force of the toggle spring 134. When sufficient fluid is expelled from the sleeve 62 the toggle spring completes the movement of the valve rod 124 to the right so that the seat 160 engages the outlet fitting 168 to shut off the flow of gas to the burner 26. This delay in the movement of the valve rod 124 and the opening of the valve 148 provides a sufficient interval of time and a sufficient flow of gas to both burners during the period of alternation to insure the lighting of the burner 24 by the burner 26 through the flash tube 50. This new cycle then continues in a similar way to the cycle just described and when the generator-absorber 20 becomes sufficiently warmed the cycle is completed and the alternation again takes place reversing the heating and reversing the flow of refrigerant in the system.

While the form of embodiment of the invention as herein disclosed, constitutes a preferred form, it is to be understood that other forms might be adopted, all coming within the scope of the claims which follow.

What is claimed is as follows:

1. Refrigerating apparatus including a twin generator-absorber system, a burner means for each of said generator-absorbers, means for supplying fuel to each of said burner means, said supply means including means for alternately changing the supply of fuel from one burner means to another, said supply means being provided with means for supplying fuel to both burner means for a limited period of time when changing the supply of fuel from one burner means to another burner means.

2. Refrigerating apparatus including a twin generator-absorber system, a burner means for each of said generator-absorbers, means for supplying fuel to each of said burner means, said supply means including means for alternately changing the supply of fuel from one burner means to the other, said supply means being provided with means for increasing the supply of fuel to the burner means when the supply is changed from one burner means to the other.

3. Refrigerating apparatus including a twin generator-absorber system, a burner means for each of said generator-absorbers, means for supplying fuel to each of said burner means, said supply means including means for alternately changing the supply of fuel from one burner means to the other, said supply means being provided with means for supplying fuel to both burner means for a limited period of time when changing the supply of fuel from one burner means to the other burner means, said supply means being provided with means for increasing the supply of fuel to the burner means when the supply is changed from one burner means to the other.

4. Refrigerating apparatus including a twin generator-absorber system, burner means for each of said generator-absorbers, means for supplying fuel alternately to said burner means, said supply means including a plurality of valves for shutting off the supply of fuel to each of the burner means, means for opening one of the valves and closing the other for permitting the supply of fuel to one of the burner means and shutting off the supply to the other, and means for holding open both of said valves when changing from one burner means to the other for a

period sufficient to light one of the burner means from the other.

5. Refrigerating apparatus including a twin generator-absorber system, burner means for each of said generator-absorbers, means for supplying fuel alternately to said burner means, said supply means including a plurality of valves for shutting off the supply of fuel to each of the burner means, means for opening one of the valves and closing the other for permitting the supply of fuel to one of the burner means and shutting off the supply to the other, means for holding open both of said valves when changing from one burner means to the other for a period sufficient to light one of the burner means from the other, and a plurality of thermostatic means responsive individually to the temperature of said generator means for controlling said valve means.

6. A two-way valve including an inlet and a plurality of outlets, a valve means for closing one outlet and opening the other, fluid pressure means for operating said valve means, and means for delaying the operation of the valve means at a point intermediate the opening of one outlet and the closing of the other for holding open two of said outlets for a period of time during the operation of the valve means.

7. A two-way valve including an inlet and a plurality of outlets, a valve means for closing one outlet and opening the other, fluid pressure means for operating said valve means, and dashpot means for delaying the operation of the valve means at a point intermediate the opening of one outlet and the closing of the other for holding open two of said outlets for a period of time during the operation of the valve means.

8. A two-way valve including an inlet and a plurality of outlets, a valve means for closing one outlet and opening the other, fluid pressure means for operating said valve means, means for holding open two of said outlets for a period of time during the operation of the valve means, a throttling means for controlling the conduction of fluid to said inlet, a by-pass for said throttling means, by-pass valve means for controlling the flow of fluid through said by-pass, and means for holding open said by-pass valve means during the operation of the other valve means.

9. A two-way valve including an inlet and a plurality of outlets, a valve means for closing

one outlet and opening the other, means for operating said valve means, and latch means for delaying the operation of the valve means at a point intermediate the opening of one outlet and the closing of the other for holding open two of said outlets for a period of time during the operation of the valve means.

10. In combination, two burner means, means for supplying fuel to each of said burner means, said supply means including means for changing the supply of fuel from either of the burner means to the other, said supply means including means for simultaneously supplying fuel to both burner means for a limited period of time when changing the supply of fuel from either of the burner means to the other.

11. In combination, two burner means, means for supplying fuel to each of said burner means, said supply means including means for changing the supply of fuel from either of the burner means to the other, means for lighting either of the burner means from the other, said supply means including means for simultaneously supplying fuel to both burner means for a period of time sufficient to light one burner means from another when changing the supply of fuel from either burner means to the other.

12. In combination, a plurality of burner means, means for supplying fuel to each of said burner means, said supply means including means for changing the supply of fuel from one of the burner means to another, means for lighting one of the burner means from another, said supply means including means for increasing the supply of fuel to the burner means when changing the supply of fuel from one burner means to another.

13. A two-way valve including an inlet and a plurality of outlets, a valve means for closing either outlet and opening the other, means for operating said valve means, snap acting means for controlling the operation of said valve means, and means for delaying the operation of the valve means at a point intermediate the opening of one outlet and the closing of the other for holding open two of said outlets for a period of time during the operation of the valve means.
